TRAVELER FOR TRANSPORTATION OF TREE TRUNKS AND LIKE LOADS

Eugen Pilet, Wimmis, Switzerland

Application March 28, 1950, Serial No. 152,306
In Switzerland February 28, 1949

6 Claims. (Cl. 212—102)

1

My invention has for its object a cableway provided with a sloping carrying rope for the transportation of tree trunks and the like. The carrying rope of said cableway that is tensioned between a high point and a loading point on a road or a railway track carries a traveller that is designed in a manner such that a tree trunk or the like load may be raised through the traction cable of the cableway up to said traveller and, as soon as the load has reached its uppermost position, the traveller is set free and may be drawn upwardly through the same traction cable over the carrying rope or else it may be allowed to sink on the latter down to the loading station. To this purpose, there is provided an automatic control in the traveller according to which the load is raised or transported towards the loading station, the automatic operation being controlled through the traction cable. This allows a considerable reduction in the time involved and in the labor required. It has already been proposed to provide in a cableway for the traction cable to raise and lower the load and also to ensure control. In such prior cableways, it is necessary to shift, for instance before transportation of the load, a special positioning apparatus over the carrying rope into the desired position and said positioning apparatus has to be clamped to the carrying rope through the agency of a special retaining cable. The present new cableway requires, on the contrary, no positioning apparatus and no auxiliary retaining cable and is consequently much simpler.

I have illustrated by way of example in accompanying drawings a preferred embodiment of my improved cableway. In said drawings:

Fig. 1 illustrates the traveller in side view.

Fig. 2 is a cross section through said traveller carriage through line II—II of Fig. 1.

Fig. 3 is a side view of the traveller with its cradle in its tilted position.

Fig. 4 is a view of a modification of the centrifugal weight, forming part of the control means.

Fig. 5 is a cross section on enlarged scale taken on line V—V of Fig. 1.

It will be appreciated that the position in which the Figures 1 and 3 appear in the drawing is not their position in actual use.

The carrying rope 1 is secured at its lower end in the immediate vicinity of the loading station in order to allow the transfer of the load onto a truck or onto a railway car. The other end of the carrying rope is anchored in ground for instance on the mountain side in a manner such

2

that said rope may be directed obliquely downwardly towards the loading station. The carrying rope may advantageously be tensioned over a gorge or deep valley that is not within easy reach and out of which tree trunks for instance are removed and easily and rapidly transported to the loading station. It is also possible for instance to provide for the transportation of ore or the like mineral products from the mountains down to the point at which they are to be worked. There is provided at the upper securing point of the carrying cable a load-controlling winch. The traveller 2 is adapted to run along the carrying rope through the agency of its four wheels 3; these wheels 3 are preferably vertically adjustable so that it is possible to move them in accordance with the curve assumed by the suspended rope and consequently to distribute uniformly the load over the four wheels. These four wheels 3 are mounted inside a carrier member 4 made of sheet iron folded into the shape of a hook. To the front side of the traveller, there is secured to the carrier member 4 a further lower carrier member 5 through the agency of bolts 6. The two carrier members 4 and 5 are outwardly folded along their lower edges and open after the manner of a hopper at 33 on the side facing the loading station. A cradle 7 is rockably secured between said carrier members 4 and 5. Said cradle is constituted by two cradle plates 8 the upper edges of which are folded at right angles so as to form running surfaces for rollers 20 to be described hereinafter. Carrier studs 9 are welded transversally to said cradle plates 8. Said studs 9 are pivotally carried in the reinforcements 16 welded to the carrier members or plates 4 and 5. To the front free ends of the carrier studs 9 are secured through the agency of screws two sectors 11 to which may be adjustably secured centrifugal masses 12. These sectors 11 form thus centrifugal masses and their object is to throw the cradle 7 from the position illustrated in Fig. 1 into the position illustrated in Fig. 3. On the inner side of the carrier members 4 and 5 are secured two arcuate stops 14. The cradle 7 is bent at this point in a manner such that it may easily move over said stops. The cradle 7 is provided with a stop 13 at its free end projecting beyond the actual traveller. The cradle is also provided at its other end with a pin 15 that is connected to the connecting rod 17 which is pivotally secured to the brake lever 16 through an adjustable point of its length.

The brake lever 16 is pivotally secured to both carrier members 4 and 5 through the agency of

the pin 18. The brake shoe 19 is pivotally secured to the brake lever 16 and its wedging action is adapted to clamp the traveller through said brake shoe to the carrying rope 1 for it to be held securely in the position considered.

To the cradle 7 is shiftably suspended the load carrier through the agency of the rollers 20. The load carrier is associated with a support 21 provided at its upper end with a catch 22. The two rollers 20 are secured to either side of said support through the agency of a pivot. At the lower end of the carrier 21 is revolubly carried a roller 23 for the traction cable 24, adapted to guide the said traction cable. To the catch 22 is pivotally secured a control rod 25 that is provided at its lower end with a control ring 26 reinforced by means of a semi-circular conical member 27. The support 21 is further provided at its lower end with two projections 28 to which are pivotally secured two carrier catches 29. The two carrier catches 29 are connected through a spring that is not illustrated and that urges the two catches 29 away from one another; that is, into the relative position illustrated in Fig. 2. The end of the traction cable 24 carries a conical weight 30 carrying in its turn the carrier ring 31 to which a tree trunk or the like load is to be secured.

In order to reduce the weight of the centrifugal mass while ensuring, however, its proper operation, it is possible, as shown in Fig. 4, to connect the oscillating mass 37 to either side of the carrier members 4 and 5, with a system of levers connected with the cradle 7, the lengths of the lever arms being selected in a manner such that the force developed by the centrifugal mass 37 may act in an amplified manner on the cradle 7. To the projecting free ends of the carrier studs 9 are secured two lever arms 34 through the agency of screws, said lever arms being connected with the connecting rods 35 and through them with the two-arm levers 36, the outer ends of which carry adjustably the actual centrifugal masses 37. These two-arm levers 36 are pivotally secured to the bolts 28 engaging the carrier members 4 and 5. The connecting rods 35 are provided with threads and their lengths may consequently be adjusted through cooperation with corresponding tapped tubular members acting as nuts and engaging said threads. One arm of the lever 36 carrying the centrifugal masses 37 is several times longer than the other arm engaging the connecting rod 35. By reason of this multiplication of forces, the centrifugal masses 37 may exert a greater force on the connecting rod 35 and consequently on the cradle 7. The object of the centrifugal masses 37 is again to urge the cradle 7 from the position illustrated in Figs. 1 and 4 into the position illustrated in Fig. 3.

The cableway described operates as follows:

In the position illustrated in Fig. 1 for a traveller, the carrying rope 1 is braked and in this position, the load-carrying means are held fast through engagement of the catch 22 with the stop 13 on the cradle in a position for which the rollers 20 on said means are arranged at the outer end of the cradle 7. The traction cable 24 can thus move downwards with the carrier ring 31 to engage the load to be raised in order to allow the latter to be secured to said ring. As soon as the load is actually secured to the ring 31, the load winch draws in the traction cable, and the load, say at tree trunk, is drawn upwardly until the conical weight 30 abuts against the control ring 26 and shifts consequently the control rod 25 upwardly, whereby the catch 22 is

released and is shifted away from the stop 13 on the cradle 7.

Now, as the load cannot be raised any higher and the catch 22 is released, the traction cable 24 draws the whole load-carrying means together with the rollers 20 over the cradle 7 towards the inner position thereof inside the traveller. At the same time, the carrier catches 29 are urged towards one another at the moment the load carrying means enter inside the traveller, said inward movement of the catches 29 being controlled through the lower parts 33 of the carrier members 4 and 5 that are bent into the shape of a hopper. The tips of the carrier catches 29 are thus urged into engagement with the underside of the weight 30 that is thus held fast by said catches. Now as soon as the load carrying means have been drawn in over the pivoting point for the cradle 7 that is over the carrier bolt 9, said cradle rocks into the position illustrated in Fig. 3. The load carrying means is held fast by the stop 14 in its inner terminal position. On the other hand the cradle 7 acting through the connecting rods 17, draws the braking lever 16 downwardly so as to shift the brake shoe 19 away from the carrier rope 1. This restores freedom of movement for the traveller over the carrying rope 1 along which said traveller may move with the load that is rigidly secured thereto. The winch may now draw upwardly the traveller through the traction cable 24 along the carrying rope 1 together with the load or else it may allow the traveller and load to sink towards the loading station. As soon as the traveller has reached the leading station, it is possible to release the load from the carrier ring 31. During this operation, the load carrier remains in its inner terminal position inside the traveller while the brake 19 remains in its released position and the traction cable 24 may be drawn in again through the winch and said cable may thus bring the traveller along the carrying rope 1 into exact vertical register over the tree trunk that is to be transported. In order to clamp however the traveller at such a point to the carrying rope, the traveller should previously be drawn up the carrying rope 1 through the agency of the traction cable 24 to a point that is about ten meters higher than is strictly necessary. At this moment, the winch is released and allowed to run backwardly so that the traction cable 24 is unwound and the traveller runs downwardly over the traction cable 1. As soon as the traveller has run downwardly again by about ten meters and is in full movement, the winch is suddenly stopped which brings the traveller also to a sudden stop. This sudden stop urges the centrifugal weights 12 and sectors 11 carrying them and consequently also the cradle 7 back into the position illustrated in Fig. 1. The load carrying means runs over the two cradle plates 8 forming the cradle 7 back into their outer terminal position.

The carrier catches 29 are urged away from one another as by spring means, not shown, so as to release the weight 30. At the same time, the catch 22 snaps into position behind the stop 13 on the cradle 7 and holds the load carrying means fast in their outer terminal position with reference to the cradle 7, while the connecting rod 17 urges upwardly the brake lever 16 and therethrough also the cable braking shoe 19, whereby the traveller is clamped to the carrying rope 1. The load controlling winch is now allowed to let the traction cable 24 move downwardly with the carrier ring 31 in order that a

further tree trunk may be secured to the latter for transportation.

The operator of the load controlling winch may be called by telephone so that he may be told of the moments at which he is to allow the winch to unwind and at which he is to stop it or else communication is obtained with him through optic signals. A marking provided on the traction cable allows the operator to be aware of the state of operation.

It is possible to locate the loading station at the upper end of the carrying rope when the tree trunks have to be removed from a lower level inside a gorge in order to bring them onto a road above said gorge.

A ropeway executed in the manner disclosed is of advantage in service inasmuch as it allows a considerable economy in time, labor and expense and provides for the easy transportation of tree trunks out of gorges and isolated valleys, the access to which is otherwise very difficult. The service of this ropeway is a very simple one and the traveller is of a simple execution and operates in a very reliable manner.

What I claim is:

1. A traveler for transportation of tree trunks and like loads over a sloping high-line comprising, in combination, a frame, means in said frame for travel over the high-line, a cradle pivotally mounted inside said frame to assume two tilted positions facing the lower and the upper end of the sloping high-line respectively, an auxiliary carriage adapted to run over said cradle, a traction cable for hoisting the load and hauling the traveler, a hoisting block secured to the free end of said traction cable, means on said auxiliary carriage for guiding said traction cable, a brake structure to engage the high-line, lever means operatively connecting said brake structure with the cradle and adapted to provide operativeness and release of said brake structure respectively according to the tilted position assumed by the cradle, means for locking the carriage to the front end of the cradle facing the lower end of the high-line, means whereby the hoisting block when brought by the traction cable into proximity with the carriage releases said locking means, the continuation of the drawing-in movement of the traction cable thus causing the carriage and the load suspended therefrom to run over the cradle to tilt said cradle into its rearwardly tilted position and thereby release the brake structure and allow movement of the traveler over the high-line in either desired direction.

2. A traveler of the class described as claimed

in claim 1, wherein the cradle carries eccentrically an auxiliary weight adapted to throw said cradle through inertia into either of its extreme tilted positions.

3. A traveler of the class described as claimed in claim 1, wherein the lever means controlling the brake structure include a connecting rod pivotally secured to the rear end of the cradle facing the upper end of the sloping high-line, and a lever pivotally secured to an adjustable point of said connecting rod pivotally carried to a point of the frame and to which the brake structure is pivotally secured.

4. A traveler of the class described as claimed in claim 1, comprising a stop at the forward end of the cradle, a catch pivotally mounted on the auxiliary carriage and adapted to engage said cradle stop when the cradle is in its forwardly tilted position facing the lower end of the high-line, and means secured to said carriage catch and adapted to release said catch through the action of the hoisting block on said means when said hoisting block has been drawn through the traction cable into its uppermost position with reference to the carriage.

5. A traveler of the class described as claimed in claim 1, wherein the auxiliary carriage comprises lateral projections and catches pivotally secured to said projections, said catches lying to either side of the uppermost location of the hoisting block, and means rigid with the cradle to urge said catches into engagement with said hoisting block as soon as the released carriage and the hoisting block begin to move over the cradle upon actuation of the traction cable.

6. A traveler of the class described as claimed in claim 1 comprising an auxiliary weight adapted to throw the cradle through inertia into either its extreme tilted positions, a leverage controlling said weight and including a first lever pivotally secured to the pivotal axis of the cradle, a connecting rod of adjustable length pivotally connected to the outer end of said first lever, and a second lever carrying the weight through one end and pivotally secured through the other end to the free end of said connecting rod and pivotally secured to the cradle body.
